UNITED STATES PATENT OFFICE.

FREDERICK DIEHL, OF ELIZABETH, NEW JERSEY, ASSIGNOR TO DIEHL MANUFACTURING CO., OF ELIZABETH, NEW JERSEY, A CORPORATION OF NEW JERSEY.

OSCILLATING FAN.

1,403,151.

Specification of Letters Patent. Patented Jan. 10, 1922.

Application filed February 6, 1919. Serial No. 275,373.

To all whom it may concern:

Be it known that I, FREDERICK DIEHL, a citizen of the United States, residing at Elizabeth, in the county of Union and State 5 of New Jersey, have invented new and useful Improvements in Oscillating Fans, of which the following is a specification.

This invention relates to an oscillating fan.

10 More particularly it relates to that type of fans in which the oscillation thereof is accomplished by mechanism driven from the fan motor.

15 A crank mechanism is ordinarily employed in a fan of this type. Heretofore the crank mechanism has been mounted for rotation in vertical bearings carried by the motor casing and a suitable link has been employed to operatively connect the crank 20 mechanism with the fixed fan support. Such a crank mechanism is objectionable, however, in that the connecting link is easily bent or broken and the operation of the entire mechanism thus impaired.

25 One object of this invention is to provide an oscillating mechanism for fans which shall be free from the above objection.

Another object is to provide an improved 30 mechanism for oscillating the head of the fan with respect to the fan support.

Another object is to provide a simple, compact, rugged mechanism for effecting the oscillation of the fan with respect to the fan support.

35 Another object is to provide improved means for adjusting the extent of oscillation of the fan.

Another object is to provide means for varying the oscillation of the fan, which 40 means may be readily operated or controlled during the operation of the fan.

Other objects and advantages will hereinafter appear.

The accompanying drawings illustrate 45 one embodiment of the invention.

The views of the drawings are as follows:

Figure 1 is a side elevation of an electric fan, portions of the mechanism being broken away to uncover normally hidden parts.

50 Fig. 2 is a horizontal section substantially on line 2-2 of Fig. 1.

Fig. 3 is an end elevation of the crank mechanism employed.

Fig. 4 is a plan partly in section of the parts shown in Fig. 2, illustrating in plan 55 the two extreme positions assumed by the crank mechanism during the oscillation of the head of the fan.

The fan illustrated in the accompanying drawings comprises in general a standard 60 1, having a base 2, and supporting the motor frame or casing 3, hereinafter referred to as the head of the fan. The casing 3 carries the fan blades 4 and guard 5. The head of the fan is pivotally mounted on the 65 standard by means of a stud 6, carried by the head and journaled in a socket 7 in the standard. Stud 6 is held against withdrawal by means of a set screw 8 projecting into an annular groove 9 in the stud. 70 The standard may be formed in two sections, as shown, hingedly connected at 10 and held in adjusted position by means of a suitable clamp screw 11.

The means hereinafter described for effecting the oscillation of the head of the fan 75 comprises a crank mechanism mounted for rotation in bearings rigidly connected with the head of the fan. The crank mechanism is driven from the armature shaft of the 80 fan motor through a suitable reducing gearing also carried by the head of the fan. A pin carried and actuated by the crank mechanism projects at all times into an opening in the fixed fan support so that upon rotation of the crank mechanism, the crank 85 mechanism and its bearings are caused to move bodily with respect to the support.

A housing 16 is rigidly connected with the motor casing 3. The housing constitutes 90 a support for the crank mechanism. It also encloses the reducing gearing by means of which the crank mechanism is driven from the motor shaft.

One end 12 of the motor armature shaft 95 is mounted in a suitable bearing 15 in the housing. This end of the motor shaft is reduced to take a worm 13, secured thereto. Worm 13 meshes with a worm gear 21 secured to the upper end of shaft 20. The 100 lower end of shaft 20 is seated for rotation in a socket 25 in the lower end of the hous-

ing while the upper end thereof is journaled in a bearing 19 formed in a plug 17. As shown, plug 17 is screwed into the upper end of the housing and forms a closure therefor.

5 A hollow plug 27 secured in an opening 26 near the lower end of the housing constitutes a bearing for the crank mechanism. The crank mechanism includes a hollow 10 shaft 29 mounted for rotation in a bearing sleeve 28 positioned in the hollow plug 27. One end of shaft 29 projects into the housing 16 and carries a worm gear 30 in mesh with a worm 23 secured to the lower end 15 of shaft 20.

20 A head 31 is secured to the outer end of shaft 29 by means of a set screw 32. As shown more particularly in Fig. 3, a circular recess 33 is provided in the end face of 25 the head. The recess is arranged eccentrically of the axis of rotation of the head and forms a seat for a crank disk 34. A face plate 35, secured to the head by screws 36, retains the disk in its seat. A crank pin 37 30 carried by the disk projects through a suitable opening in the face plate.

35 A plunger 38 is slidably mounted in a suitable bore 39 in the head. The plunger is yieldingly pressed against the periphery 30 of the disk by means of a spring 41. A screw 42 is positioned in the outer end of the bore bears against the spring and controls the tension thereof.

40 The plunger is designed to cooperate with 35 the notches 40 in the periphery of the disk to restrain rotation of the disk in its seat. As shown, one side or base of each of the notches 40 merges into the peripheral wall of the disk while the other side forms an 45 abrupt shoulder 43 therewith. By this construction the plunger 38 yieldingly resists rotation of the disk in its seat in a clockwise direction (Fig. 3) and by engagement with shoulder 43 positively prevents such 50 rotation in a counter-clockwise direction. In order that the flat end of the plunger may squarely abut the base of the notch 40, the plunger is so mounted that its longitudinal axis is slightly offset from a position radially 55 of the disk.

55 An open sided socket 44 is provided in the upper section of the fan standard. The crank pin 37 is so mounted as to project at all times into this socket. A cylindrical member 45 is seated for rocking movement in the socket and is provided with a longitudinally extending slot 46. The slot is of sufficient width to slidably take the projecting end of the crank pin. The crank pin 60 65 may be provided with a bearing sleeve 47 to engage the walls of the slot. Member 45 is inserted into the socket 44 through the upper open end thereof.

65 The operation of the mechanism thus far described may be briefly summarized as fol-

lows. Upon rotation of the motor armature shaft a slow rotation, in a clockwise direction (Fig. 3), is imparted to shaft 29 and head 31 through the reducing gearing hereinbefore described. The engagement of 70 plunger 38 with shoulder 43 prevents relative rotation of crank disk 34 with respect to the head 31. Consequently, crank pin 37 is caused to move in a circular path concentric with the axis of rotation of the head. 75

During this movement, crank pin 37 travels up and down in slot 46 of member 45. Since the pin is confined in this slot, the relative horizontal movements between the pin and the center of rotation of the 80 crank mechanism causes a relative horizontal, bodily movement of the crank mechanism with respect to the standard. The crank mechanism is, however, mounted in bearings rigidly connected with the pivoted 85 head of the fan. The bodily movements of the crank mechanism result, therefore, in the oscillation of the head of the fan with respect to the fan standard.

Figure 4 illustrates the two extreme positions assumed by the crank mechanism during the oscillation of the head of the fan. It will be noted that pin 37 projects at all 90 times into the socket 44 and that rockable member 45 insures a positive connection between pin 37 and the standard and yet permits necessary variations in the angular relation between the crank pin and standard.

95 Portions of the standard adjacent the socket 44 are shown cut away as at 54 to 100 provide clearance for the pin 37. These cut away portions do not, however, extend the full length of the socket. As shown in Fig. 1, the extreme upper end of the standard is left intact so as to provide projections 55 105 which embrace the cylindrical member 45.

100 Means may be provided for adjusting the extent of oscillation of the head of the fan. Upon rotation of the disk in its seat in a clockwise direction (Fig. 3) the distance of 110 pin 37 from the axis of rotation of head 31 may be varied. One position to which the pin may be thus adjusted is indicated in dotted lines in Fig. 3.

115 The mechanism shown for causing rotation of the disk 34 in its seat includes a pinion 49 mounted concentrically of the disk and in mesh with pinion 50 secured to one end of shaft 51. Shaft 51 is rotatably mounted in hollow shaft 29 and extends through a 120 suitable aperture in the wall of housing 16. A burr 52 is secured to the free end of this shaft by a set screw 53.

125 The disk 34 and pin 37 may be adjusted while the crank mechanism is at rest by rotating shaft 51 with its pinion 50 in a counter-clockwise direction (Fig. 3). Such rotation of pinion 50 will cause a clockwise rotation of pinion 49 and disk 34 relative to head 31. The disk may thus be rotated 130

until the next succeeding notch 40 comes beneath the plunger 38 or until pin 37 reaches the dotted line position.

During the normal rotation of the head 5 31, disk 34, pin 37, and pinion 49 are bodily carried about the axis of rotation of the head which axis coincides with the longitudinal axis of shaft 51. The interengagement of pinion 49 with pinion 50 causes shaft 51 to rotate with the head and at the same speed. An adjustment similar to that above described may therefore be accomplished while the crank mechanism is rotat- 10 ing by grasping burr 52 and holding shaft 51 against rotation. This causes relative rotation of the disk with respect to the head in the same direction as that above de- 15 scribed. It is obvious, however, that a quicker adjustment may be obtained by actu- 20 ally rotating burr 52 and shaft 51 in a direction contrary to the direction of rotation of head 31 while the crank mechanism is in operation.

The foregoing is a detailed description of 25 one specific embodiment of the invention. It will be understood that the detailed description is for the purpose of making clear the construction and operation of one form of the invention and should not therefore be 30 construed as a limitation upon the invention.

What I claim is:

1. In an oscillating fan the combination of a support having an opening therein, a 35 head portion, including a fan motor, pivotally mounted above said opening on said support for rotation about a vertical axis, a crank mechanism carried by said head portion and having a pin pro- 40 jecting into the opening in said support, and means operatively connected with said fan motor for actuating said crank mechanism, and bodily moving same through an arc outside of the opening in the support.

45 2. In an oscillating fan the combination with a head portion, a support therebelow having a slot, an inwardly extending pin carried by said head portion and mounted for sliding movement in said slot, and means 50 for imparting a rotary motion to said pin with respect to said head portion to oscillate said head portion in a horizontal plane above said support.

55 3. An oscillating fan having a support, a head portion pivotally mounted for move- 60 ment about a vertical axis above said support, and means for oscillating said head portion in a horizontal plane above said support, said means including a crank mechanism carried by said head portion below the point of pivotal support and rotatable in a plane parallel to the pivotal axis of said head portion.

65 4. In an oscillating fan the combination of a support, a head portion above the sup-

port and pivotally mounted thereon, and means for oscillating said head portion with respect to said support in a horizontal plane, said means including a crank mechanism carried by and below said head portion and rotatable about an axis extending substantially radially of the pivotal axis of said head portion.

5. In an oscillating fan the combination of a standard having a vertically extending opening therein, a motor pivotally mounted on said standard for movement about a vertical axis, an inwardly extending pin supported by said motor casing and extending into the opening in said standard, and means for bodily rotating said pin about an axis extending substantially radially of the standard to oscillate said casing with respect to said standard in a substantially horizontal plane.

85 6. In an oscillating fan the combination of a support, a vertically extending guide mounted therein for movement about a vertical axis, a head portion pivotally mounted on said support for movement about a vertical axis, an inwardly extending crank pin carried by the head and co-operating with the guide, means for bodily moving said pin relative to said head in a vertical plane, and means for adjust- 90 95 ing the position of said pin relative to the guide to vary the arc of oscillation of said head.

7. In an oscillating fan including a sup- 100 port and a head mounted thereon for rotation about a vertical axis, means for oscillating said head including a crank mechanism mounted for rotation in a vertical plane, an inwardly extending crank pin adjustably mounted on said mechanism, and 105 means operatively connected with said pin and extending along the axis of rotation of said mechanism for adjusting the position of said pin to vary the arc of oscillation.

110 8. In an oscillating fan having a stand- 115 ard and a head portion pivotally mounted on the standard for oscillation in a horizontal plane, comprising means for positively oscillating said head, said means comprising a vertical guide rotatably mounted in the standard, and a crank mechanism carried by the head and operatively connected with the guide.

120 9. An oscillating fan comprising a sup- 125 port, a head portion pivotally mounted on the support for oscillation in a horizontal plane, and means for positively oscillating said head, said means including a vertically extending guide way in the support below the head and a crank mechanism carried by the head and having a pin rotatable about a horizontal axis, said pin extending into said guide whereby a relatively large angle of oscillation for the head is effected.

by a relatively small movement of the crank pin.

10. In an oscillating fan the combination of a support, a head portion pivotally mounted thereon for oscillation in a horizontal plane, crank mechanism carried by and extending below the head, said mecha-

nism having a pin arranged to rotate in a vertical plane adjacent said support, and vertical guiding means in the support adapted to receive said pin. 10

In witness whereof, I have hereunto subscribed my name.

FREDERICK DIEHL.
